UNITED STATES PATENT OFFICE.

FRANCIS W. ROBINSON, OF RICHMOND, INDIANA, ASSIGNOR TO THE ROBINSON & COMPANY, OF SAME PLACE.

STRAW-STACKER.

SPECIFICATION forming part of Letters Patent No. 535,296, dated March 5, 1895.

Application filed December 5, 1894. Serial No. 530,897. (No model.)

To all whom it may concern:

Be it known that I, FRANCIS W. ROBINSON, a citizen of the United States, residing at Richmond, in the county of Wayne and State 5 of Indiana, have invented certain new and useful Improvements in Straw-Stackers, of which the following is a specification.

My invention has reference to straw stackers or straw stacking attachments for use in 10 connection with thrashing machines, and more particularly to that class of such devices known as pneumatic or "wind" stackers.

It relates to the mounting of the trunk and to the means for rendering it telescopic, or 15 variable in length. I have devised a novel and efficient way of holding, guiding and supporting the rotatable turn table which carries the trunk or chute; and have simplified and made more efficient the means for moving and 20 adjusting the movable outer telescopic trunk section upon the inner section.

I will first describe my improvements by reference to the accompanying drawings and will then point out in the claims those features which I believe to be new and of my 25 own invention.

In the drawings Figure 1 is a side elevation of a mechanism embodying my improvements. Fig. 2 is an enlarged plan of the turn 30 table. Fig. 3 is a section on line 3—3 Fig. 2, showing also in section the "stump," or extreme lower end, of the trunk or chute. Fig. 4 is a section on an enlarged scale, and in the line of its axis, of the hood operating reel. Fig. 5 is an axial section of the spring device 35 by which the hood is caused, when permitted, to swing or turn in a direction opposite to that in which it is swung, by the reel.

The turn table A is annular and has as usual 40 upon its rim, worm teeth to engage its driving worm B which is operated in the usual manner. This annular turn table heretofore has, so far as I am informed, been supported by devices applied to its inner edge. Under 45 my invention it is supported at its outer edge or rim, the rim for this purpose being received between the horizontal flanges c of pulleys or anti-friction revoluble wheels C mounted upon vertical axes d in housings D. There 50 may be any suitable number of these wheels.

In practice I find three are sufficient. They are placed around the exterior of the turn table at equal distances apart, and they serve most effectually to support the turn table as well as to steady its movements and to prevent it from any lateral slip. The periphery of that part of the wheels which runs in contact with the rim of the turn table is shaped to fit snugly the general contour of the rim (in vertical section). One advantage attending the arrangement is that I am enabled to attach the stump E of the trunk or chute directly to the turn table, by fitting the lower end of the stump over an annular flange on the turn table, and then directly bolting the two together, as indicated in Fig. 3, instead of connecting the two together by stay rods extending from the upper end of the stump to the turn table, as is necessary when the turn table supporting devices are applied to the inner edge of the table.

The shaft B' of the driving worm B, is supported at the end which carries the worm, in two bearings b b between which the worm is placed, and these bearings have horizontal 75 lips or flanges b' b' which extend inwardly so as to overhang the rim of the turn table and serve to hold down the table against the weight of the rearwardly extending trunk, thus relieving the flanged antifriction wheels 80 C from the excessive strain which might otherwise come upon them.

F is the inner trunk section which is mounted upon the stump E to swing up and down thereon as usual, and is provided with the 85 customary derrick arrangement f'.

G is the outer or telescopic section arranged to slide back and forth on the inner section for the purpose of varying the working length of the trunk.

In the position in which the parts are shown in Fig. 1, the sections are closed upon one another to shorten as far as possible the length of the trunk. In this position, the inner section extends to the end of the outer section, 95 and it has beyond that a semi-circular extension f' surrounding which is a similar semi-circular extension of the outer section. When the outer section is extended fully its rear end is very near the front tubular end of the in- 100

ner section, and the object of the extension f' is to afford the requisite bearing for the outer section under these conditions.

- The outer section is moved lengthwise of the other, by means of a wire rope h or the like, one end of which is made fast to a post h' on the rear end of the outer section. This rope thence extends back to a drum h^2 around which it makes several turns to prevent slip, thence passes forward to and around a pulley h^3 on a post h^4 attached to the rear or inner section, and thence extends back to the rear end of a guide rod or pipe h^5 to which it is attached. This rod passes loosely through a guide eye or hole in the post h^4 , and is attached to the post h' as well as to a second post h^6 at the front of the outer section G. By turning the drum the outer section will be moved lengthwise in one direction or the other upon the inner section according to the direction of rotation of the drum. The guide rod assures and steadies the outer section during the movement and prevents it from rotating upon the inner section.
- The hood H at the outer end of the outer section G, turns upon an axis i and is adjusted by means of a cord or rope K operated from the base of the stacker by means of a reel I upon which it is wound. The working length of this operating cord should vary according to the variations in the working length of the trunk. To this end I construct the reel I so that it will automatically give or render the cord when the trunk is extended. For this purpose the reel is friction held being mounted loosely upon an axle l and held thereon between a shoulder l' and a friction disk l^2 pressed against the reel by a spiral spring l^3 encircling the axle, the degree of compression of which is regulated by an adjusting nut l^4 screwing upon the axle. Under this arrangement when the outer section is extended the reel I will automatically render enough of cord k to permit this movement. When the outer section is drawn in, the slack of cord k is of course taken up by turning the reel by hand. The cord k turns the hood H in one direction only. To turn it in the other direction I provide a spring actuated device, shown in Fig. 5, which tends constantly to turn the hood in a direction opposite to that in which it is pulled by the operating cord k . In this device the axle l is held immovably to the extension g of the outer section G and upon it is loosely hung the hood. Surrounding the axle is a spiral spring m received in a cylindrical housing n and having one of its ends attached to the hood and its other end attached to the housing. The housing n at its closed outer end is fashioned as a nut n' which screws upon the screw-threaded outer end of the axle i and beyond this point, is a separate lock nut n^2 . By turning the housing nut, the tension of the spring m can be adjusted to the required point. In extending the outer section, the spring m will of course give before the friction reel I does, so that the cord k will pull

down the hood to its full extent, before the friction reel renders; but when once the proper length of trunk is obtained, it is a matter of a moment only to turn the reel so as to readjust the hood to desired position.

It will be noted that between the posts h' and h^6 extends an inclined rod h^7 which is higher at rear than at front, and from the post h' extends the taut wire cable or rope h at a downward inclination to the drum h^2 at rear. These devices form a truss like structure which is of material assistance in giving stability to the trunk when it is in extended condition.

Having now described my improvements and the best way now known to me of carrying the same into effect, what I claim herein as new and of my own invention is as follows:

1. In combination with the worm-toothed turn-table, and its operating worm, the anti-friction wheels for supporting said turntable journaled upon vertical axes and placed around or upon the exterior of the turn table, and provided with peripheral flanges between which the rim of the turn table fits and is supported and held.

2. In combination with the worm toothed turn table, the antifriction wheels for supporting said turn table journaled upon vertical axes around or upon the outside of the turn table, and provided with peripheral flanges between which the rim of the table fits and is supported and held, and the worm and worm shaft supported in bearings having inwardly projecting flanges, which overhang the turn table, substantially as and for the purposes hereinbefore set forth.

3. The combination of the inner trunk section F, the outer telescopic longitudinally movable section G, the rope h fast at one end to the rear end of section G and at the other end to the rear end of a rod h^5 connected to and extending rearwardly from the section G, said rope extending from the point to which it is attached to the rear section back to and around an operating windlass or drum on the inner section F, thence forward to and around a pulley on said section F, and thence back to rod h^5 , under the arrangement and for joint operation, as hereinbefore shown and described.

4. The combination with the inner section F, and the outer slideable telescopic section G, of the hinged hood carried by said outer section, a frictionally held reel on the inner section, a cord extending from said reel to the hood for moving the latter in one direction, and a spring device which tends to move the hood in a direction opposite to that in which it is moved by the cord, substantially as and for the purposes hereinbefore set forth.

5. The combination of the inner section F, the outer slideable telescopic section G; the guide rod h^5 attached to section G and extending back through a guide eye or sleeve on the inner section F; the windlass or drum h^2 ; the

rope h fast to a post on the rear end of the outer section and extending thence back to and around the windlass forward to and around pulley h^3 on section F and back to rod 5 h^5 ; and the inclined rod h^7 , under the arrangement and for joint operation substantially as hereinbefore set forth.

6. The toothed annular turn table and the trunk or chute "stump" attached directly to 10 the inner rim of the same, in combination with anti-friction wheels journaled upon ver-

tical axes around the periphery of the turn table, and provided with flanges to receive and support the outer rim of the same, substantially as and for the purposes hereinbefore set forth. 15

In testimony whereof I have hereunto set my hand this 1st day of December, 1894.

FRANCIS W. ROBINSON.
